UNITED STATES PATENT OFFICE.

RALPH W. WILSON, OF NEW YORK, N. Y.

SHAKER TOP OR CAP.

1,386,044.

Specification of Letters Patent.

Patented Aug. 2, 1921.

Application filed May 8, 1920. Serial No. 379,858.

To all whom it may concern:

Be it known that I, RALPH W. WILSON, a citizen of the United States, and resident of the borough of Manhattan, in the city and 5 State of New York, have invented a new and useful Improvement in Shaker Tops or Caps, (Case II,) of which the following is a specification.

The object of my invention is to provide 10 a novel shaker top or cap which will be practically powder tight, which will be very easy to manipulate and which will be inexpensive to manufacture and attractive in appearance.

15 A further object is to provide a shaker top or cap in which the shutter member is held frictionally between the inner and outer perforated top or cap members and movable to open and close the perforations in said inner 20 and outer members, the location of the shutter member giving a much neater appearance to the receptacle to which the top or cap is applied and also protecting the shutter member from injury and from exposure 25 to dust and dirt.

A further object is to provide a shutter member which is held in position by friction, thereby eliminating the necessity and expense of using a separate spring.

30 A still further object is to provide certain improvements in the construction, form and arrangement of the several parts whereby the device is materially simplified and rendered more effective for the purposes intended.

35 Practical embodiments of my invention are represented in the accompanying drawings, in which—

Figure 1 represents in side elevation a 40 portion of a receptacle with one embodiment of my invention applied thereto.

Fig. 2 represents a top or cap in top plan, the regulable shutter member being shown in its closed position.

45 Fig. 3 represents a vertical section on an enlarged scale taken in the plane of the line III—III of Fig. 2.

Fig. 4 represents a vertical section on an 50 enlarged scale taken in the plane of the line IV—IV of Fig. 2.

Fig. 5 represents the shutter member in perspective.

Fig. 6 represents in vertical central section another embodiment of my invention.

55 The top or cap may be made of sheet metal or other suitable material capable of being

formed into the required shape. This top or cap comprises the inner perforated top or cap member 1, the outer perforated top or cap member 2 and the interposed regulable 60 shutter member 3.

The perforations 4 in the inner top or cap member 1 are always in alinement with the perforations 5 in the outer top or cap member 2. The perforations 6 in the interposed 65 shutter member 3 are arranged to be brought into and out of alinement with the perforations 4 and 5 as the shutter member 3 is moved back and forth into its opened and closed positions.

70 This interposed shutter member 3 is frictionally held between the inner and outer top or cap members 1 and 2 and it is provided with oppositely disposed finger pieces 7 and 8, which project through slots 9 and 10 in the side walls 11 of the outer top or cap member 2. These side walls 11 of the outer top or cap member 2 overlap and are permanently secured to the side walls 12 of the inner top or cap member 1. These side 75 walls 12 of the inner top or cap member may be an integral part of the side walls of the receptacle 13 as shown in Figs. 1 to 4 inclusive, or they may be screw-threaded as shown at 14 in Fig. 6, so that the top or cap 80 may be removably attached to the screw-threaded neck 15 of a bottle or other receptacle 16.

85 The inner top or cap member 1 is provided with a depressed portion 17 and a raised 90 peripheral portion 18. This raised peripheral portion 18 is omitted where the oppositely disposed finger pieces 7 and 8 are located. This raised peripheral portion 18 snugly engages the inner face of the outer 95 top or cap member 2, thus forming a powder tight joint which is very desirable.

95 The means which I have shown for yieldingly holding the shutter member 3 in its opened or closed position is as follows:

100 The shutter member 3 is provided with a downwardly extended projection 19 which is caused to snap into either one of the two depressions 20 or 21, in the face of the inner top member 1 as the shutter is moved into its opened or closed position. The inner top or cap member 1 is sufficiently yielding to allow the projection 19 to pass from one to the other of the depressions 20, 21.

110 It is evident that various changes may be resorted to in the construction, form and arrangement of the several parts of my top or

cap without departing from the spirit and scope of my invention; hence I do not wish to limit myself to the particular embodiments herein shown and described, but

5. What I claim is:—

1. A shaker top or cap comprising perforated inner, outer and intermediate members of thin sheet material, said intermediate member being provided with oppositely disposed finger pieces projecting through the side walls of the outer member for use in reciprocating the intermediate member, and means for yieldingly holding the intermediate member opened or closed, said means being arranged to spring one of the members out of its normal position as the intermediate member is reciprocated.

2. A shaker top or cap comprising perforated inner, outer and intermediate members of thin sheet material, the inner member having integral converging side walls forming a shoulder and the outer member having integral converging side walls overlapping and permanently secured to the side walls of 25 the inner member, the intermediate member being slideable back and forth across the top of the cap between the inner and outer members, and the inner member being crowned to frictionally press the intermediate member 30 against the outer member.

3. A shaker top or cap comprising perforated inner, outer and intermediate members of thin sheet material, the inner member having integral converging side walls forming a shoulder and the outer member having integral converging side walls overlapping and permanently secured to the side walls of 35 the inner member, the intermediate member being slideable back and forth across the top of the cap between the inner and outer members, the inner member being crowned to frictionally press the intermediate member 40 against the outer member, and means for yieldingly holding the intermediate member 45 opened or closed, said means being arranged to force the inner and outer members apart as the intermediate member is moved between its opened and closed positions.

4. A shaker top or cap comprising inner 50 and outer perforated members and an intermediate perforated shutter member reciprocable transversely of the top or cap, all of said members being of thin sheet material, the inner member having a raised peripheral 55 portion engaging the outer member and a depressed central portion forming a seat for the shutter member, the inner member pressing the shutter member against the outer member, the shutter member being provided 60 with oppositely disposed finger pieces projecting through the side walls of the outer member, the raised peripheral portion of the inner member having breaks therein forming seats for said finger pieces, the depressed 65 portion and the breaks in the raised portion

of the inner member being of a depth substantially equal to the thickness of the shutter member and its finger pieces, to form a powder tight joint.

5. A shaker top or cap comprising inner 70 and outer perforated members and an intermediate perforated shutter member reciprocable transversely of the top or cap, all of said members being of thin sheet material, the inner member having a raised peripheral 75 portion engaging the outer member and a depressed central portion forming a seat for the shutter member, the inner member pressing the shutter member against the outer member, the shutter member being provided with 80 oppositely disposed finger pieces projecting through the side walls of the outer member, the raised peripheral portion of the inner member having breaks therein forming seats for said finger pieces, the depressed portion 85 and the breaks in the raised portion of the inner member being of a depth substantially equal to the thickness of the shutter member and its finger pieces, to form a powder tight joint, the inner member having integral side 90 walls and the outer member having integral side walls overlapping and permanently secured to the side walls of the inner member.

6. A shaker top or cap comprising inner 95 and outer perforated members and an intermediate perforated shutter member reciprocable transversely of the top or cap, all of said members being of thin sheet material, the inner member having a raised peripheral portion 100 engaging the outer member and a depressed central portion forming a seat for the shutter member, the inner member pressing the shutter member against the outer member, the shutter member being provided with oppositely disposed finger 105 pieces projecting through the side walls of the outer member, the raised peripheral portion of the inner member having breaks therein forming seats for said finger pieces, the depressed portion and the breaks in the 110 raised portion of the inner member being of a depth substantially equal to the thickness of the shutter member and its finger pieces, to form a powder tight joint and means for yieldingly holding the shutter member 115 opened or closed.

7. A shaker top or cap comprising inner 120 and outer perforated members and an intermediate perforated shutter member reciprocable transversely of the top or cap, all of said members being of thin sheet material, the inner member having a raised peripheral portion 125 engaging the outer member and a depressed central portion forming a seat for the shutter member, the inner member pressing the shutter member against the outer member, the shutter member being provided with oppositely disposed finger pieces projecting through the side walls of 130 the outer member, the raised peripheral por-

- tion of the inner member having breaks therein forming seats for said finger pieces, the depressed portion and the breaks in the raised portion of the inner member being of 5 a depth substantially equal to the thickness of the shutter member and its finger pieces, to form a powder tight joint, and means for yieldingly holding the shutter member opened or closed, said means being arranged 10 to force one of the members out of its normal position as the shutter member is moved between its opened and closed positions.
8. A shaker top or cap comprising inner and outer perforated members and an intermediate perforated shutter member reciprocable transversely of the top or cap, all of said members being of thin sheet material, the inner member having a raised peripheral portion engaging the outer member and 15 a depressed central portion forming a seat for the shutter member, the inner member pressing the shutter member against the outer member, the shutter member being provided with oppositely disposed finger pieces projecting through the side walls of 25 the outer member, the raised peripheral portion of the inner member having breaks therein forming seats for said finger pieces, the depressed portion and the breaks in the raised portion of the inner member being of 30 a depth substantially equal to the thickness of the shutter member and its finger pieces, to form a powder tight joint, and means for yieldingly holding the shutter member opened or closed, comprising a projection 35 and recessed connection between the shutter member and one of the other members, said connection serving to force said members apart as the shutter member is moved between its opened and closed positions. 40
- In testimony, that I claim the foregoing as my invention, I have signed my name this third day of May, 1920.

RALPH W. WILSON.
